(57) **CLAIM**

The ornamental design for a personal tracking device as shown and described.

DESCRIPTION

FIG. 1 is a perspective view of a personal tracking device.

FIG. 2 is another perspective view of the personal tracking device.

FIG. 3 is a rear view of the personal tracking device.

FIG. 4 is a front view of the personal tracking device.

FIG. 5 and FIG. 6 are side views of the personal tracking device.

FIG. 7 is a top view of the personal tracking device.

FIG. 8 is a perspective view of a head of a personal tracking device.

FIG. 9 is another perspective view of the head of the personal tracking device.

FIG. 10 is another perspective view of the head of the personal tracking device.

FIG. 11 is a top view of the head of the personal tracking device.

FIG. 12 is a bottom view of the head of the personal tracking device.

FIG. 13 is a back view of the head of the personal tracking device.

FIG. 14 is a front view of the head of the personal tracking device.

FIG. 15 and FIG. 16 are side views of the head of the personal tracking device.

FIG. 17 is a perspective view of a bracelet of the personal tracking device.

FIG. 18 is another perspective view of the bracelet of the personal tracking device.

FIG. 19 is another perspective view of the bracelet of the personal tracking device.

FIG. 20 is another perspective view of the bracelet of the personal tracking device.

FIG. 21 is a bottom view of the bracelet of the personal tracking device.

FIG. 22 is a top view of the bracelet of the personal tracking device.

FIG. 23 and FIG. 24 are side views of the bracelet of the personal tracking device; and,

FIG. 25 and FIG. 26 are end views of the bracelet of the personal tracking device.
